UNITED STATES PATENT OFFICE

JOHN ZRNEL, OF CLEVELAND, OHIO

SHOE CLEANING DEVICE

Application filed July 3, 1930. Serial No. 465,658.

This invention relates to shoe cleaners and has special reference to that type of shoe cleaner which is usually placed at the door of a house, on the running board of an automobile or other like place to enable a person to clean the sole and edges of their shoes before entering.

One important object of the invention is to improve the general construction of devices of this character.

A second important object of the invention is to provide a novel combined scraper and brush arrangement in such a cleaner.

A third important object of the invention is to provide a novel arrangement of attaching and supporting means for the brushes used herein whereby the brush bristle will be supported for the greater part of their lengths.

20 A fourth important object of the invention is to provide a novel arrangement whereby lightness is obtained without unduly sacrificing strength.

With the above and other objects in view, 25 the invention consists in general of certain novel details of construction and combinations of parts hereinafter more fully described, illustrated in the accompanying drawings and specifically claimed.

30 In the accompanying drawings, like characters of reference indicate like parts in the several views, and:

Figure 1 is a plan view of the cleaner;

Figure 2 is a side elevation thereof;

35 Figure 3 is a bottom view thereof;

Figure 4 is a section on the line 4-4 of Figure 1;

Figure 5 is a section on the line 5-5 of Figure 1.

40 The frame of this device is preferably made as an integral casting and includes front and rear bars 10 which are offset upwardly in the central portions to provide feet 11. Side bars 12 connect the upper parts of the bars

45 10 between the feet and transverse bars 13 extend in spaced relation between the side bars 12. These bars 10, 12 and 13 have their upper edges in the same plane and the bars 10 and 13 form the scraper proper. Brace

50 bars 14 connect the bars 10 and 13 between

the side bars 12 and are arranged with their lower edges in the same plane as the bottom edges of the feet 11 and their upper edges below the upper edges of the bars 10 and 13 so that these bars 14 support the bars 10 and 13 but do not interfere with the scraping action of the latter. Notches 15 are formed in the bottom edges of the bars 14 to lighten these bars but the notches 15 of one bar 14 are in staggered relation to the notches 15 of the other bar 14 so as not to weaken the bracing and supporting effect of these bars to any undue extent.

Brush backs 16 are fitted between the feet 11 and are secured thereto by screws 17 in such positions that the bristles 18 on one side are supported by the respective bars 12, these bristles projecting only slightly above said bars 12. On the other side of each brush back is mounted a brace angle 19 having its upper edge in the plane of the upper edges of the bars 12 and bearing against the bristles to securely support the same on this side.

Perforated lugs 20 are formed between the lower parts of the central bars 13 at each end thereof so that screws may be inserted therethrough for securing the device in any desired position.

In use the rough dirt or mud is removed from the shoes by scraping them on the bars 80 10 and 13 after which they are rubbed over the bristles 18.

There has thus been provided a simple and efficient device of the kind described and for the purpose specified.

While there is herein shown and described the preferred embodiment of the present invention, it is nevertheless to be understood that minor changes may be made therein without departing from the spirit and scope 90 of the invention as claimed.

Having thus described the invention, what is claimed is:

1. In a shoe cleaner, a frame including a plurality of scraper bars and having front and back bars extending downwardly at their opposite ends to form feet, brushes having backs secured between the feet at each side of the frame with the lower faces of the back lying in the same plane as the lower ends 100

of the feet and having bristles extending slightly above the frame, said frame also having side bars at the inner ends of said feet, the bristles at the inner sides of the brushes bearing against said side bars, bristle supporting angles fixed to the brush backs at their outer sides and bearing against the bristles at said sides, and brace bars connecting said scraper bars and having their upper edges below the upper edges of the scraper bars and their lower edges in the plane of the lower edges of the feet to provide an intermediate support for the scraper bars.

2. In a shoe cleaner, a frame including a plurality of scraper bars and having front and back bars extending downwardly at their opposite ends to form feet, brushes having backs secured between the feet at each side of the frame with the lower faces of the back lying in the same plane as the lower ends of the feet and having bristles extending slightly above the frame, said frame also having side bars at the inner ends of said feet, the bristles at the inner sides of the brushes bearing against said side bars, bristle supporting angles fixed to the brush backs at their outer sides and bearing against the bristles at said sides, said scraper bars, side bars and angles having their upper edges in the same horizontal plane, and brace bars connecting said scraper bars and having their upper edges below the upper edges of the scraper bars and their lower edges in the plane of the lower edges of the feet to provide an intermediate support for the scraper bars.

In testimony whereof I affix my signature.
JOHN ZRNEL.
